[57] **CLAIM**

The ornamental design for a elongated card scratcher with a key chain, as shown and described.

DESCRIPTION

FIG. 1 is a perspective view of an elongated card scratcher with a key chain showing my new design. The broken line showing of a lottery card is for illustrative purposes only and forms no part of the claimed design;

FIG. 2 is a side view thereof. The side opposite that shown in FIG. 2 is a mirror image of the side shown in FIG. 2; FIG. 3 is a front view thereof. The side opposite that shown in FIG. 3 is a mirror image of the side shown in FIG. 3; and, FIG. 4 is a bottom plan view thereof.

The broken line showing on the key chain is intended to represent the remaining portions of the key chain that are not shown for ease of illustration.
